UNITED STATES PATENT OFFICE.

AARON STRAUS AND MAX B. JACOBY, OF ST. LOUIS, MISSOURI; SAID JACOBY
ASSIGNOR TO SAID STRAUS.

CHAIR ATTACHMENT.

SPECIFICATION forming part of Letters Patent No. 405,919, dated June 25, 1889.

Application filed November 2, 1888. Serial No. 289,805. (No model.)

To all whom it may concern:

Be it known that we, AARON STRAUS and MAX B. JACOBY, both of the city of St. Louis, in the State of Missouri, have invented a certain new and useful Improvement in Chair Attachments, of which the following is a full, clear, and exact description, reference being had to the accompanying drawings, forming part of this specification, and in which—

10 Figure I is a perspective view illustrative of our invention and showing part of a chair with a rocker attached. Fig. II is a perspective view of one of the rockers and its clips. Fig. III is a detail view showing part of one 15 of the legs of the chair, part of the rocker, and the clip, the latter being in section taken on line III III, Fig. V. Fig. IV is a vertical section of the clip, taken on line IV IV, Fig. VI. Fig. V is a vertical section taken on line V 20 V, Fig. IV. Fig. VI is a transverse section showing a modified means of securing the clips to the rockers.

Our invention relates to an attachment for securing rockers to ordinary chairs, the invention being of such a nature that any ordinary 25 rocker may be secured to any ordinary chair by any unskilled person, as all that is necessary to be done is to cut holes or slots in the rockers to receive a connecting screw or pin.

30 We are aware that it is not broadly new to attach rockers to ordinary chairs, but in most, if not all, instances the rockers are especially formed for that purpose, whereas with our invention any common form of rocker may be 35 attached to the chair, and that also without materially changing the elevation of the chair.

Our invention consists in features of novelty hereinafter fully described, and pointed out in the claims.

40 Referring to the drawings, 1 represents the seat of a chair of any ordinary construction, and 2 the legs. But part of the seat and but two of the legs are shown.

3 represents a rocker of any usual or common 45 shape, and 4 represents clips securing the rocker to the legs of the chair.

The only thing necessary to be done to form the connection between the rocker and legs is to perforate the rocker to receive a connecting bolt or screw 5 of each clip. The perfora-

ration is preferably made in the form of a slot 6 at the rear end of the rocker and a mere round perforation or hole at the front end; but, if desired, the perforations at the front end may also be in the form of a slot, as shown 55 by dotted lines in Fig. I. The object of making the slot or slots is to permit of an adjustment of the clips to or from each other, so that they may be shifted to suit the legs of different chairs which are not of equal distances apart.

Our preferred manner of securing the clips to the rockers is to form projections 8 on the clips, (see Fig. V,) which enter the slots or perforations 6, these projections being hollow to 65 receive the screws 5, between the heads of which and the rockers washers 9 are placed. Instead, however, of using the projections 8, they may be dispensed with, as shown in Fig. VI, and the screws pass through the slots 6 of 70 the rockers into the body of the clips.

The clips are made of two parts, each connected together by set-screws 10 and guidepins 11. Each clip has a socket 12 to receive the legs of the chair, and by tightening on the 75 screws 10 (after the legs are inserted in the clips) it will be seen that the two parts of the clip will be moved toward each other, and thus clamp the leg of the chair. The pin 11 forms a guide for the clip on the opposite side 80 to the set-screw 10, and is simply cast on or secured to one part of the clip and enters a hole or socket in the other part. The bottom of each part of the clip has preferably a flange or extension 13, that forms a bottom to the 85 socket of that part of the clip, and upon these flanges the ends of the legs 2 rest.

With our improved attachment it will be observed that the elevation of the chair is not changed materially, and that any ordinary 90 rocker may be attached to any ordinary chair by simply perforating it to receive connecting bolts or screws 5.

We claim as our invention—

1. In an attachment for chairs, the combination of the clips, consisting of two parts each fixed to one side of each rocker, connecting bolts or screws for securing the clips to the rockers, one part of each clip being substantially fixed and the other part adjust- 95 100

able, the latter having guide-pins on one side and the former having sockets to receive the pins, and a fastening securing the outer edges of the parts together, substantially as set forth.

2. In an attachment for chairs, the clips consisting each of two parts having bottom flanges 13, set-screws 10, connecting said parts on one side, pins 11 on the other side of one

part received by sockets in the same side of the other part, and screws 5, for connecting the clips to the rockers, substantially as and for the purpose set forth.

AARON STRAUS.
MAX B. JACOBY.
